SPIRAL WHIRLING TOY

Ernest J. Swimmer, 340 E. 52nd St., New York, N.Y.

Filed Dec. 8, 1964, Ser. No. 82,956

Term of patent 7 years

(Cl. D34—15)

FIG. 1

FIG. 2

FIGURE 1 is a perspective view of a spiral whirling toy showing my new design, with the side of the male figure not shown having a typical facial representation and the side of the female figure not shown having a typical back representation;

FIGURE 2 is a side elevational view thereof.

I claim:

The ornamental design for a spiral whirling toy, as shown and described.
